(57) CLAIM

I claim the ornamental design for a male brief harness, as shown and described.

DESCRIPTION

FIG. 1 is a perspective view of a male brief harness showing my new design;

FIG. 2 is a view in front elevation thereof;

FIG. 3 is a view in rear elevation thereof;

FIG. 4 is a view in front elevation thereof in an inside-out configuration; and,

FIG. 5 is a view in rear elevation thereof in an inside-out configuration.

The portion of FIG. 4 bordered by broken lines represents unclaimed environment only and forms no part of the claimed design.
